STEAM DRIER

Pasquale Pascale, New York, N. Y., assignor to
Novo Patents, Inc., a corporation of Delaware

Refiled for abandoned application Serial No.
465,049, June 30, 1930. This application Sep-
tember 5, 1936, Serial No. 99,647

2 Claims. (Cl. 183—108)

This invention relates to a steam drier, especially adapted for use in connection with the boiler of locomotive, marine and stationary engines and is a substitute application for my abandoned application filed June 30, 1930, Ser. No. 465,049.

The structure about to be described involves the same principle as that which characterizes the locomotive valves shown and described in various patents heretofore granted to me, and the main purpose of this invention, like that expressed in said patents, is to dry or denude the steam of moisture and thereby improve its quality before it passes to the super-heater or other point, where it is utilized. However, in the present invention, there is no control of the steam in passing through the drier and therefore, the device cannot be considered as a valve, as the steam is permitted to pass freely through the structure and it is capable of handling the maximum amount of steam that the engine requires.

The invention contemplates the provision of a compact structure in which the steam in entering the casing or body of the drier is interrupted and denuded of a portion of its moisture and directed toward a perforated cylinder, through whose perforations the steam passes after a further quantity of moisture has been taken out, there being provided within the chamber formed in the main by the perforated cylinder, means primarily intended to direct the steam toward the center of the chamber and in a downward direction for the purpose of minimizing eddy current losses.

The invention further contemplates means for returning to the boiler, the water extracted from the steam.

In the drawings illustrating the invention.

Figure 1 is a partial section and elevation of a drier constructed in accordance with my invention, the drier being shown within the dome of a locomotive.

Figure 2 is a sectional plan taken on line 1—1 of Figure 1.

Figure 3 is a detail fragmentary section of a portion of the lower part of the drier body, showing the formation of the lower part of the body that includes the drainage chamber.

Referring to the drawings, the numeral 1 designates the upper part of the body or casing, the numeral 2 the lower part. These two parts are connected by what I term a turbine 3, which is constituted by a ring 4 having therein numerous

5 atten-
uated openings 6, through which the steam primarily enters in passing into the drier body. The means for connecting this ring with the upper and lower portions 2 of the body is a series of short bolts 7, as clearly shown in Figure 2. The ring 4 is preferably made up of a plurality of sections, six being shown, and each being provided with ears 8 apertured for the passage of short bolts 9, by which the ring sections are secured together. It will be noted that the vanes 10 in the sections are so shaped that the steam in passing through the turbine will be in a direction tangential to the axis or center of the drier and as shown, even the vanes in an individual section are differently directed or shaped, thus 15 providing an element of the structure that causes the steam currents to be thoroughly mixed.

The upper part of the body is provided with a conical dome 10 secured thereto by bolts 11, the central portion of the dome being provided with 20 an eye bolt 12, which serves as a means for conveniently lifting or handling the drier when all of the parts are assembled.

The numeral 13 designates the inner wall of the lower part of the casing, and this inner wall, 25 together with the outer wall, forms a substantially U-shaped drainage chamber 14, having openings 15 in the bottom thereof, which will be later referred to. Within this chamber is an annular diaphragm 16 which extends entirely 30 around the body or casing and within the same. This diaphragm is secured to the top section 1 by bolts 16a, and to the lower section of the body or casing by bolts 17, the bolts being provided with heads 16' at the upper portion and 17' at 35 the lower, there being nuts 16'' and 17'' on the ends of the bolts within the diaphragm, as shown. Interposed between the sections 1 and 2 of the drier body and the diaphragm 16, and surrounding the bolts 16 and 17, are similar sleeves 18 40 which serve to properly space the diaphragm 16 from the outer wall of the casing, the diaphragm being held a little closer to the outer wall of the lower part of the casing, than to the inner wall.

Seated in an annular recess 19 in the upper edge of the inner wall 13, is a cylinder 20 provided with numerous small perforations or nozzles 21, through which the steam must pass before passing to the connection that leads to the superheater. The upper end of this perforated cylinder is retained in an annular groove or rabbet 22, formed on the under side of the outer edge of the conical dome 10. The inner upper edge of the part 1 bears against the upper edge 55

of the cylinder, and the bolt 11, which serves to connect the dome with the upper part of the casing, serves also to hold the upper portion of the cylinder in rigid position.

5 The numeral 23 designates the outlet or service pipe for connection with the superheater or other means for conducting the steam to the point where it is utilized. This pipe is provided with a flange 24, which is secured thereto by a 10 number of bolts 25. Threaded into the flange 24 is a connection 26 connected by an elbow 27 to a valve fitting 28, through which the water extracted from the steam, passes back into the boiler, the water being admitted to the pipe 26 15 through the openings 15 in the floor of the drainage chamber 14.

By spacing the diaphragm 16 from the upper and lower portions or sections 1 and 2 and from the turbine ring, a barrier is formed by said 20 diaphragm that prevents the steam, as it enters the spaces between the vanes from passing directly to the perforations in the cylinder 20. The steam as intimated, in passing through the narrow spaces between the vanes, is divided into 25 attenuated streams that, by reason of the arrangement or shape of the vanes, is directed in different directions and greatly broken up, and in this breaking, the steam is denuded of a very considerable portion of its mixture that falls 30 to the bottom of the drainage chamber. The steam then passes in an upward direction, into the space between the diaphragm and the wall of the perforated chamber, and then passes through the perforations in the cylinder and in 35 so passing, the steam is denuded of further moisture which also falls into the drainage chamber and is led therefrom back into the boiler. As the steam passes into the perforated cylinder and especially through the upper portion of the 40 cylinder, it is directed against the conical dome 10 of the cylinder and is deflected downwardly and since this movement takes place throughout the entire surface of the cylinder, the steam will be deflected downwardly toward the outlet or 45 service pipe in the same general direction, thus minimizing, as before stated, eddy current losses.

It will be understood that while this drier is especially adapted for locomotive boilers, it is obvious that it may be employed in any situation with proper modifications where a super-

heater may be used or omitted, as the exigencies of the particular case may require.

What I claim is:

1. In a steam drier, in combination, a hollow casing having inlet openings in its wall, an outlet opening, and a closed top, a drying element within the casing and provided with numerous perforations and spaced from the casing wall and extending to the top of the casing, a diaphragm surrounding the drying element and spaced both 10 from the casing wall and said element with its upper end terminating below the perforations in the upper area of the drying element and forming with the wall of the casing and the drying element inner and outer conduits, whereby steam 15 entering said inlet openings impinges said diaphragm, precipitating its excess moisture thereon, and is deflected upwardly in said outer conduit and flows in part through said perforations positioned above said diaphragm, and in part 20 through the perforations below the top of the diaphragm.

2. In a steam drier, in combination, a hollow casing comprising upper and lower sections, a cone shaped closure for the upper section extending downwardly into the casing, the lower section being formed with inner and outer imperforate walls annularly spaced and connected by a bottom portion having drainage openings therethrough, a ring engaged between the wall of 30 the upper section and the outer wall of the lower section and having inlet openings therein, a drying element within the casing and interposed between inner wall of the lower section and said closure and having numerous perforations there- 35 in, a diaphragm surrounding the drying element and spaced both from the casing wall and said element with its upper end terminating below the perforations in the upper area of the drying element, and forming with the wall of the casing 40 and drying element inner and outer conduits, whereby steam entering the inlet openings impinges said diaphragm, precipitating its excess moisture thereon, and is deflected upwardly in the outer conduit and flows in part through the 45 perforations positioned above the diaphragm and against the cone shaped closure, and in part through the perforations below the top of said diaphragm, and an outlet opening for the casing.

PASQUALE PASCALE. 50
